UNITED STATES PATENT OFFICE.

RAY E. DE CAMP, OF WILKINSBURG, PENNSYLVANIA, ASSIGNOR TO WESTINGHOUSE ELECTRIC AND MANUFACTURING COMPANY, A CORPORATION OF PENNSYLVANIA.

RELAY.

1,368,326.

Specification of Letters Patent. Patented Feb. 15, 1921.

Application filed October 8, 1918. Serial No. 257,349.

To all whom it may concern:

Be it known that I, RAY E. DE CAMP, a citizen of the United States, and a resident of Wilkinsburg, in the county of Allegheny and State of Pennsylvania, have invented a new and useful Improvement in Relays, of which the following is a specification.

My invention relates to electromagnets and electromagnetically actuated switches for the control of electric switches. In a more limited aspect, my invention relates to switches that are particularly adapted for unit-switch-control systems.

Control systems of the unit-switch type, largely used for governing electric motors, comprise a plurality of independently operated individual switches or contactors designed and connected to act successively to produce a gradual acceleration of the motors with which they are associated. In these systems, devices are ordinarily employed for delaying the action of the successive contactors in order to avoid injury to the motors by excessive currents. One form of these devices comprises a plurality of auxiliary switches or relays for governing the closing of the respective contactors. My invention comprises a relay which, though adapted for general use, finds particular application in connection with such a system. In my application for current-limit relay, Serial No. 241,259, filed June 21, 1918, I have illustrated several forms of such a relay. The present application is concerned with a modification.

I have illustrated my invention in connection with a unit-switch accelerating system, in which the closing of each contactor is controlled by a coil, the circuit of which is closed by a relay. The time of closing of the relay is determined by the degree of energization of another coil. Though this arrangement is by no means essential, I have illustrated the second coil as serving also the function of a blowout coil for the contactor. As in the above-mentioned application, the relay is biased toward closed position but is maintained open until the motor current falls to the proper value, the current itself, thus performing the work of releasing the relay at the proper time.

An object of my invention is to provide

a novel relay for particular use in a unit-switch accelerating system.

Another object of my invention is to provide a relay, the controlling coil of which serves also as a blowout coil for one of the contactors.

Other objects of my invention will appear hereinafter.

In the drawings, Figure 1 is a partly elevational and partly longitudinal sectional view of my relay, and Fig. 2 is a diagrammatic view of circuits and apparatus illustrating the use of this relay in a motor-accelerating system.

Referring to Fig. 1, the relay parts are supported, in any suitable manner, upon an insulating panel 1. A pair of magnetizable pole pieces 2, lined with insulating material 3, inclose a coil 4 between them, which, when energized by current flowing through it, creates a magnetic field for attracting a plunger 5 and an armature 6. A compression spring 7 serves to return the plunger 5 to normal position upon the de-energization of the coil 4. The force exerted by the spring 7 may be varied by a rod 8, the position of which, with respect to the plunger 5, may be adjusted, as by means of a screw-threaded connection 81. The plunger 5 is slidably mounted in a non-magnetizable tube 9, which, together with a magnetizable core 10, is located within the opening of the coil 4. The rod 8 is slidably mounted in the core 10 and within an opening in the armature 6 and is provided with an enlargement 11 for normally engaging the armature 6, thereby to maintain this armature 6 in engagement with the core 10. The core 10 is adjustably secured to the tube 9 at 12, the tube 9 and the core 10 being respectively provided with flange members 13 and 13^a for clamping the parts of the arc shield together. As the flange 13 is of non-magnetizable material, it serves also to prevent "freezing" of the plunger 5. The parts are so designed as normally to leave an adjustable air gap 14 between the core member 10 and the plunger 5 for the purpose of regulating the reluctance of the magnetic circuit. The coil 4 is insulated from the core 10 at 15.

Although I have illustrated the plunger 5 as controlling a single armature 6, it

will be obvious that, as explained in my aforementioned application, the plunger 5 may be easily so designed as to control a plurality of armatures 6, each controlling a 6 relay, as hereinafter described.

The armature 6 is pivotally secured at 16 to a supporting member 17 mounted upon the panel 1. A spring 18 is coiled about a rod 19, which is rigidly secured to the 10 panel 1, and which passes through an opening in an arm 20 of the armature 6, this armature 6 being preferably, as illustrated, of bell-crank shape. The tension of the spring 18 may be so adjusted, as by means 15 of nuts 31, as to exert a force weaker than that of the spring 7. The arm 20 carries a movable contact member 24 for coöperating with a stationary contact member 26 which is mounted upon the panel 1. The 20 contact members 24 and 26 constitute a relay. Obviously, the contact member 24 may be supported by the main portion of the armature 6 and, again, as illustrated in my above-mentioned application, the main 25 portion of the armature 6 and the arm 20 may both serve to support contact members.

The coil 4, which may be a series or a shunt coil, is adapted to be energized upon the closing of a contactor 45 and to serve as 30 a blowout coil for this contact member.

The operation is as follows: Upon the closing of the contactor 45, (Fig. 2), current flows through the coil 4, whereupon a magnetic field is created which causes the 35 plunger 5 to be drawn into the opening in the coil 4 toward the core 10. The rod 8 is thereby forced outwardly, the engagement between the part 11 and the armature 6 being thereupon released. If the current 40 is above a previously selected safe value, the magnetic field will overcome the force of the spring 18, and the armature 6 will remain in engagement with the core 10. When the current falls to a safe value, the spring 45 18 will overpower the force of the magnetic field of the core 4 and cause the closing of the contact members 24 and 26. In the event that the magnetic field becomes too weak to maintain the plunger 5 in actuated position, 50 in opposition to the force of the spring 7, this spring 7 will reactuate the plunger 5 to its illustrated position (Fig. 1) causing the enlargement 11 to reengage the armature 6 and to reopen the contact members 24 and 55 26 in opposition to the force of the spring 18.

In Fig. 2, I have illustrated a control system embodying the use of the relay of Fig. 1. For convenience, I employ the same reference numerals as in Fig. 1, wherever 60 possible. An armature 38, having a compensating field-magnet winding 39, a series field-magnet winding 40 and a shunt field-magnet winding 41 is connected between the line conductors 42 and 43 in series with a 65 resistor 44. The circuit of the motor is

adapted to be closed by the line contactor 45, and the resistor 44 is adapted to be short-circuited by a plurality of contactors 45^a, 45^b and 45^c. The contactor 45 is actuated by a coil 52, and the contactors 45^a, 45^b 70 and 45^c are actuated by coils 48, 49 and 50. A plurality of relays 6, 6^a and 6^b are shown as mechanically interlocked with the plungers 5, 5^a and 5^b, respectively, of the blowout coils of the contactors 45, 45^a and 45^b in such 75 fashion that they will be maintained in the open position until released upon the occurrence of current peaks, as described in connection with Fig. 1. The system is shown as controlled by a pair of push-buttons respectively designated as "start" and "stop". The contactor 45 is mechanically interlocked with a switch 51 for short-circuiting the "start" push-button, as below 80 described. 85

Upon the closing of the "start" push-button, a circuit is established which extends from the line conductor 42, through the "stop" and "start" push-buttons, and the actuating coil 52 to the line conductor 43. 90 The contactor 45 is thereupon closed, causing the closing also of the switch 51, which establishes a short-circuit for the "start" push-button, so that the "start" push-button may thereupon be released. A circuit is now 95 established for the motor which extends from the line conductor 42 through the coil 4—which controls the relay 6—the contactor 45, the armature 38, the field-magnet windings 39 and 40 and the resistor 44, to 100 the line conductor 43. A shunt circuit is also established for the field-magnet winding 41. A heavy current is thus caused to flow through the blowout coil 4 which operates the plunger 5 and releases the relay 6. 105 The relay 6, though released mechanically upon the occurrence of a current peak is, nevertheless, maintained in open position for a limited period of time until the current in the motor circuit falls to a previously selected safe value, as explained in connection with the description of Fig. 1. When the current falls to a sufficiently low value, the relay 6 closes, as described in connection with Fig. 1, whereupon a circuit is 110 established from the line conductor 42, through the "stop" push-button, the relay 6 and the actuating coil 48 of the contactor 45^a, to the line conductor 43. The closing of this circuit, causing the energization of the 115 actuating coil 48, results in the closing of the contactor 45^a which establishes a short-circuit for a portion of the resistor 44 through the coil 4^a, the energization of this coil 4^a resulting also in the establishment of 120 a blowout field for the contactor 45^a and the actuation of the plunger 5^a to release the relay 6^a. The energization of the coil 4^a, of course, results in maintaining open the relay 6^a for a limited period of time. When 125 130

the current falls to a second predetermined safe value, depending upon the strength of the spring 18 (Fig. 1), connected to the relay 6^a, or the size of the air gap 14 (Fig. 1), the relay 6^a will close, whereupon a circuit will be established, which extends from the line conductor 42, through the "stop" push-button, the relay 6^a and the actuating coil 49 of the contactor 45^b, to the line conductor 43. The contactor 45^b will thereupon be closed to short-circuit another portion of the resistor 44, the coil 4^b, which is then energized, serving also as a blowout coil for the contactor 45^b. In the same manner as described above, the relay 6^b will close at the proper time to cause the energization of the coil 50 and the consequent closing of the contactor 45^c to short-circuit the remaining portion of the resistor 44. The "stop" push-button serves to deenergize the various circuits and stop the motor.

It will be understood that the circuits of Fig. 2 are illustrative only, and that my invention is of general application, not necessarily limited to motor-accelerating systems. I desire, therefore, that my invention shall not be construed as limited except in so far as limitations may be expressed in the appended claims.

30 I claim as my invention:

1. The combination with a coil and a plunger slidable within the opening of said coil, of means for actuating said plunger outwardly from said opening when said coil is deenergized, an armature controlled by said plunger, means controlled by said plunger for maintaining said armature adjacent to said coil, and means for biasing said armature away from said coil.

2. In a switch mechanism, a coil, a pair 40 of insulating barriers inclosing said coil and a core member and a tube member clamping said barriers to said coil.

3. In a switch mechanism, a coil, a stationary core member located within the 45 opening of said coil and having a longitudinal opening, a plunger adapted to be attracted to said core member, a rod movable with said plunger and slidably mounted in said longitudinal opening, an armature that 50 is movable relatively to said rod, means carried by said rod for controlling said armature and means for actuating said armature.

4. In a switch mechanism, the combination with a coil and a switch associated 55 therewith, of a spring tending to close said switch, a spring-retracted plunger controlled by said coil for maintaining the switch open when the coil is deenergized and an armature for maintaining the switch 60 open a predetermined time after the coil has been energized.

5. In a switch mechanism, the combination with a main switch having a blowout coil, of an auxiliary switch, a spring-retracted plunger associated with the blowout coil for maintaining the auxiliary switch in an open position, and an armature connected to the auxiliary switch and associated with the blowout coil for maintaining the 70 auxiliary switch in an open position a predetermined time after the blowout coil is energized and the auxiliary switch is released by the plunger.

In testimony whereof, I have hereunto 75 subscribed my name this 26th day of Sept., 1918.

RAY E. DE CAMP.
